UNITED STATES PATENT OFFICE.

CHRISTIAN HOLM, OF BOWMAN, NORTH DAKOTA.

EXPANSIBLE CORE.

1,337,910.

Specification of Letters Patent. Patented Apr. 20, 1920.

Application filed November 10, 1919. Serial No. 886,903.

To all whom it may concern:

Be it known that I, CHRISTIAN HOLM, a citizen of the United States, residing at Bowman, in the county of Bowman and

5 State of North Dakota, have invented certain new and useful Improvements in Expansible Cores, of which the following is a specification, reference being had to the accompanying drawings.

10 This invention relates to expansible cores, and has relation more particularly to a device of this general character especially designed and adapted for use in connection with the vulcanizing of tire casings or the like, and it is an object of the invention to provide a novel and improved device of this general character wherein the expanding members of the core coat with an external pad of yielding or compressible material,

15 whereby a casing or a portion thereof, to be vulcanized, is placed under equal pressure on all sides, and with requisite compensation made for all high and low places which may be upon the inside of the casing.

20 Another object of the invention is to provide a novel and improved core of this general character comprising a main arcuate body having members threaded therethrough for endwise movement, and wherein the 25 outer ends of said members are in swivel engagement with an expanding shoe overlying the outer or tread portion of the main members.

An additional object of the invention is 30 to provide a novel and improved device of this general character wherein a supplemental shoe overlies the inner portion of the main member of the core, and which is entirely detached therefrom.

35 Furthermore it is an object of the invention to provide a novel and improved expansible core for use in connection with the vulcanizing of a tire casing whereby the use of air bags now generally employed, may be

40 dispensed with, etc.

The invention consists in the details of construction and in the combination and arrangement of the several parts of my improved expansible core whereby certain important advantages are attained and the device rendered simpler, less expensive and otherwise more convenient and advantageous for use, as will be hereinafter more fully set forth.

45 The novel features of my invention will hereinafter be definitely claimed.

In order that my invention may be the better understood, I will now proceed to describe the same with reference to the accompanying drawings, wherein:

60

Figure 1 is a view partly in section and partly in side elevation of an expansible core constructed in accordance with an embodiment of my invention;

Fig. 2 is a sectional view taken substantially on the line 2—2 of Fig. 1, and,

Fig. 3 is a sectional view taken substantially on the line 3—3 of Fig. 1.

As disclosed in the accompanying drawings, M denotes the main member of my improved core, and which member is preferably tubular and longitudinally curved, in accordance with the requirements of practice.

45 The wall of the member M adjacent the opposite ends thereof is provided with the diametrically opposed openings 2, and through which opposed openings is loosely directed the elongated shanks 3. Each of the shanks 3 is threaded through a member 4 or nut, positioned within the bore of the member M, and of a size and configuration whereby the same is held against rotary movement.

50 S denotes an outer or tread shoe of a length substantially equal to the length of the main member M, and which is curved longitudinally and transversely for contact throughout its length with the adjacent or outer portion of the member M. The adjacent end portions of the shanks 3 are in

55 swivel connection, as at 5, whereby the shoe S may be moved toward or from the main member M upon requisite rotation being imparted to the shanks 3. The opposite or inner end portions of the shanks 3 are provided with the cross bars 6 or the like, whereby the desired rotation of said shanks may be conveniently obtained through the medium of a manual operation.

90

60 S' denotes a second shoe which is of a longitudinal and transverse configuration to snugly engage the inner or upper face of the main member M, and this shoe is of a length to substantially bridge the space between the shanks 3. This shoe S' preferably loosely lies in applied position.

65 Substantially surrounding the assembly core is a padding P, and which padding preferably comprises a plurality of superimposed laminations 7 of yieldable and compressible material. It is preferred that the

95

100

105

110

laminations 7 be produced from discarded inner tubes, because in practice such laminations after the device has been used a few times, will gradually become vulcanized into almost a solid mass, although the padding operates equally well whether the laminations are separate or united.

The operation of the device is believed to be obvious from the foregoing description, 10 although it might be well to state that by requisite rotation of the shanks 3, the shoe S will be moved away from the main member M and thus force and expand the padding P against the inside of the casing, resulting in equal pressure on all sides of the casing, and at the same time compensating for all high or low places which may be 15 upon the inside of the casing.

In practice it has been demonstrated that 20 a core constructed in accordance with an embodiment of my invention is substantially indestructible, as the only part which wears out is the padding P, and this can be renewed at a very slight expense.

25 Another decided advantage of the present invention is the provision in the padding P whereby discarded or worn out inner tubes can be employed, as use is given to material which otherwise has been generally 30 considered worthless.

It is also believed to be obvious that with the use of the present device it is unnecessary to employ the air bags, as is now generally done, as it has been firmly established 35 in actual practice that the present device can be used with much better results than that obtained by the use of air bags.

From the foregoing description it is thought to be obvious that an expandible 40 core constructed in accordance with my invention is particularly well adapted for use by reason of the convenience and facility with which it may be assembled and operated and it will also be obvious that my invention is susceptible of some change and modification without departing from the principles and spirit thereof, and for this reason I do not wish to be understood as 45 limiting myself to the precise arrangement and formation of the several parts herein shown in carrying out my invention in practice except as hereinafter claimed.

I claim:

1. An expandible core for use in connection with the vulcanizing of tire casings 50

comprising a main arcuate member, members disposed through and in threaded engagement with the opposite end portion of said main member, and a shoe overlying the outer portion of the main member, and with which the second named members are in swivel engagement.

2. An expandible core for use in connection with the vulcanizing of tire casings 65 comprising a main arcuate member, members disposed through and in threaded engagement with the opposite end portion of said main member, a shoe overlying the outer portion of the main member, and with which the second named members are in 70 swivel engagement, and a padding of yielding material substantially surrounding the main member and the shoe.

3. An expandible core for use in connection with the vulcanizing of tire casings 75 comprising a main arcuate member, members disposed through and in threaded engagement with the opposite end portion of said main member, a shoe overlying the outer portion of the main member, and with which the second named members are in 80 swivel engagement, a padding of yielding material substantially surrounding the main member and the shoe, and a second shoe overlying the inner portion of the main 85 member.

4. An expandible core for use in connection with the vulcanizing of tire casings comprising a main arcuate member, members disposed through and in threaded engagement with the opposite end portion of 90 said main member, a shoe overlying the outer portion of the main member, and with which the second named members are in swivel engagement, a padding of yielding 95 material substantially surrounding the main member and the shoe, and a second shoe overlying the inner portion of the main member, and separate therefrom.

5. In combination with an expandible core 100 of the class described, a yieldable padding surrounding said core.

6. In combination with an expandible core of the class described, a yieldable padding surrounding said core, said padding comprising superimposed laminations. 105

In testimony whereof I hereunto affix my signature.

CHRISTIAN HOLM.
